(57) **CLAIM**

The ornamental design for a stepping exerciser with rolling wheels, as shown and described.

DESCRIPTION

FIG. 1 is a perspective view of a stepping exerciser with rolling wheels showing my new design;

FIG. 2 is a front side elevational view thereof;

FIG. 3 is a rear side elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view thereof;

FIG. 9 is a perspective view thereof; and,

FIG. 10 is a perspective view thereof.

The broken line showings of the handle assemblies in FIGS. 8, 9 and 10 are included for the purpose of illustrating environmental structure and form no part of the claimed design.
